METHOD AND APPARATUS FOR HEAVY-MEDIA SEPARATION

Edmund C. Bitzer, Golden, Colo., assignor to
Colorado Iron Works Company, Denver, Colo.,
a corporation of Maine

Application August 16, 1943, Serial No. 498,743

15 Claims. (CL 209—173)

1

This invention relates to a method and means for heavy-media separations of ore concentration, and more particularly relates to improvements in spiral classifiers of the well known "Akins" type, by which such apparatus is adapted for heavy-media separations.

As a result of relatively recent developments, heavy-media separations have proven particularly efficacious in the treatment of low grade ores and certain other types of materials which cannot be processed economically by older ore dressing methods. As an example, iron and manganese-ferous iron ores have been successfully treated by these methods, as have various lead and zinc ores.

In the operations heretofore in use, spiral classifiers have been employed in the process as "densifiers," providing a density-regulating means in advance of the actual heavy-media separation. This heavy-media separation has been performed in conical tanks, and where large tonnages are treated by these methods a considerable amount of head room has to be provided, due to the shape of the tank. Also, in the present treatment cones, the proportion of ore to liquid in the material under treatment is relatively small, for which reason machine sizes are large in proportion to the tonnage of ore treated.

It is an object of the present invention to provide a simple, economical and efficient heavy-media separation in which there is a relatively high proportion of solid to liquid in the material under treatment.

Another object of the invention is to provide a simple, economical and efficient heavy-media separation in which a relatively large tonnage of material taken for treatment is processed in a plant of limited size.

A further object of the invention is to provide selective controls of the factors of density, pulp ratio and treatment time in a heavy-media separation.

Still another object of the invention is to provide a novel type of classifier apparatus suited for performing heavy-media separations.

Other objects reside in novel steps and treatments and novel combinations and arrangements of parts, all of which will be described in the course of the following description.

While the present invention may be practiced in a variety of ways and in a variety of apparatus, the accompanying drawings illustrate a typical treatment and typical structural embodiments for performing the treatment. In the drawings in the several views of which like parts have been designated similarly.

Figure 1 is a diagrammatic flow sheet representation of the arrangement of equipment utilized in performing a heavy-media separation according to the present invention.

2

Figure 2 is a side elevation of a classifier of the "Akins" type, partially broken to show in section the arrangement of parts adapting it for heavy-media separations;

5 Figure 3 is a plan view of the separation chamber of the classifier illustrated in Figure 2, seen from the approximate position of the lines 3—3 in Figure 2;

10 Figure 4 is an end elevation of the classifier shown in Figure 2, viewed from the pool-forming end of the tank;

Figure 5 is a section taken along the line 5—5, Figure 2; and

15 Figure 6 is a fragmentary side elevation, partially broken, of the reciprocating rake type classifier embodying features of the present invention.

The practice of the present invention will be best understood by citing a typical treatment. In this case an iron ore from Minnesota iron 20 range and comprising a mixture of iron ore and gangue minerals was selected as the product for treatment. The heavy-media employed in the operation is ferro silicon having a specific gravity of 6.7 and employed in varying degrees of density throughout a continuous operation.

25 The treatment will be best understood by reference to the flow sheet, Figure 1. Ore taken for treatment is delivered by a suitable conveyor 6 onto a washing screen 7. The fine ore separated by this screening action is collected at 8 and is discharged from the circuit and passed to a separate fine ore treatment.

30 The oversize screened product of the separation is collected at 9 and then is passed to a heavy-media separator 10. This separator involves a novel design and operation in heavy-media separations, the details of which will be explained hereinafter. The raked product or sink concentrate is discharged at 11 and passed to a sink 35 washing screen 12. The sink concentrate product of this separation is delivered onto a conveyor 13 and discharges as the final product of the treatment.

35 The float product of the heavy-media separation passes to a float drainage and washing screen 15. In this operation most of the heavy medium in the overflow from the heavy-media separator is formed as one product at 16 and flows to a pump 19 which returns the heavy medium so

40 separated to mix with the incoming ore as the feed to heavy-media separator 10. Such heavy medium as does not drain readily at 16 is washed off the float product by water sprays and is collected as a light density liquid at 17.

45 The light density liquid collected at 14 from the float drainage and washing screen 15 is moved by a pump 20 to a thickener 22 and prior to its delivery into the thickener the liquid is 50 passed through magnetizing blocks 21. The thick-

ener overflow is passed to a water clarification thickener 32, while the sludge is moved into a primary magnetic separator 23.

The tailings 25 of the primary separator treatment constitute the feed to a secondary magnetic separator 26. The tailings 28 of this secondary separation are passed to waste or to a water recovery treatment, while the primary concentrate 24 and the secondary concentrate 27 are conducted as the feed to a densifier 29.

This latter unit which is a modified type "Akins" classifier has been in use in heavy-media separations. The overflow product of the densifier is delivered into the water clarification thickener 32. The densified product is discharged and collected at 30, and then subjected to the action of a demagnetizing coil 31.

The product of the latter action is then mixed with the ore feed and return medium being delivered into the heavy-media separator 10. This circuit simplifies the treatment procedure in heavy-media separations of iron ores and the like, and this simplification is due largely, if not entirely, to the efficiency of the separator 10, the construction and operation of which will be described now.

Figures 2, 3, 4 and 5 illustrate a typical embodiment of the invention. In this form, the tank 10 is normally positioned in an inclined position and has at its lower end a separation compartment 34, the details of which will be described hereinafter. A sink concentrate discharge outlet (not shown) is located at the upper end of the tank.

A spiral conveyor 35 mounted on a shaft 36 extending through the tank from the compartment 34 to the upper end of the tank moves settled solids through a conveying and drainage zone to the sands discharge. The shaft is supported in a swivel bearing 37 at the upper end and at its lower end is connected with a lifting mechanism 38. A motor 39 drives the shaft through the provision of suitable gearing 40.

The swivel bearing and lifting mechanism are conventional features in the "Akins" classifiers sold by Colorado Iron Works Company, and such features, per se, form no part of the present invention.

The feed compartment 34 is formed by a sloping end wall 41, having an overflow lip 42 at its upper end, and a partition 43 which extends completely across the tank but terminates in spaced relation to the bottom of the tank to provide a passage 44 between compartment 34 and the interior of tank 10. Preferably, this partition will be mounted in tank 10 for adjustment to different elevations to vary the size of passage 44.

A feed-box 45 is located in the upper portion of compartment 34 and has open ends to admit and direct feed into said compartment. A splitter member 46 is positioned beneath the feed-box and serves to distribute solids descending therefrom.

For some purposes it may be necessary to exert a crowding action on the float material and this is provided for by adjustable partitions 47 which may be selectively positioned in one of a series of cooperative slots in partition 43 and end wall 41.

The slots have not been shown because the scale of the drawings does not permit, but the several positions of adjustment are indicated by the dotted line representations of Figures 3, 4 and 5. With this understanding of the structural arrangement of the form of the invention shown in Figure 2, the operation will be described now.

When the structure shown in Figure 2 is used

in heavy-media separations, such as that shown in Figure 1, the media returned from densifier 29 and recirculated by pump 19 mixes with incoming ore from washing screen 7 and is fed into feed-box 45. Due to the capacity and action of the separator 10, this intermixture may contain a relatively large quantity of iron ore.

The intermixture, thus introduced, descends through the feed box and then separates, with a light siliceous matter rising to the surface, while the heavy iron ore and some ferro-silicon descend and pass through passage 44 into the conveying and drainage zone. The splitter 46 distributes the matter so descending before it passes into the conveying and drainage zone and thus provides a uniform sink concentrate load throughout the extent of the spiral.

The material passed into the conveying and drainage zone is moved progressively by the spiral until it travels out of the pool and finally reaches the sink concentrate discharge. Liquid, inclusive of the heavy-media suspension, drains from the ore as it passes upwardly from the pool and as a consequence the iron product so separated requires very little subsequent treatment, and may have a moisture content of as little as 10%.

The siliceous matter rising to the surface of the body in compartment 34 is overflowed across lip 42, and some of the heavy media passes with it. The walls 47 exert a crowding action on the siliceous matter rising to the surface, and to accommodate volume and density variations, these walls are adjustable to vary the superficial area and volume of this separation zone. In this way, a superelevation can be created within the pool which further assists the separation.

The arrangement of the separation compartment 34 permits the operator to see what is happening in the separation zone, and by making relatively small volumetric adjustments, operation under optimum conditions can be effectively maintained.

In the case of shutdowns, the rakes 35 can be raised by lifting mechanism 38 which rotates shaft 36 about swivel bearing 31. When operation resumes, the blades are dropped back gradually until the shaft reaches its normal operating position, and in this way damage to the mechanism from excessive stresses is avoided.

The unit illustrated in Figure 6 employs the same type of heavy-media separation. The tank 10a of this form is mounted at an inclination and has a sloping end wall 50 having an overflow lip 51 in its upper surface. Material settling in tank 10a is moved to an upper sink concentrate discharge (not shown) by rakes 52 which are moved in a reciprocating cycle by mechanism 53, the details of which are conventional.

The tank 10a is divided by a partition 54 into a separation zone 55 connecting with the conveying and drainage zone through a passage 56. A feed-box 57 adjoins partition 54 at its top for the supply of material to be treated and heavy-media to the compartment 55. A splitter 58 divides and distributes the incoming material before the heavier material travels through passage 56 into the conveying and drainage zone.

The action in compartment 55 is identical with that hereinbefore described with reference to compartment 34 of Figure 2. After the solids enter the conveying and drainage zone they are moved by the rake mechanism 52, 53 to an upper point of discharge with heavy-media draining back into the pool.

While the separation can be performed ef-

fectively in the apparatus of Figure 6, the apparatus of Figure 2 comprises a preferred embodiment of the invention because of the efficiency of the raking action employed therein. The raked material is maintained in a progressive state of movement, insuring more uniform density control and preventing any overloading of the mechanism that might occur due to slippage of the load of raked product.

If desired, a washing action may be utilized with this treatment whenever extra dilution is not undesirable. In such case the conveying and drainage zone will be provided with a wash box assembly of the type shown and claimed in Dickson application Serial No. 471,989, filed January 11, 1943, for Classifier apparatus.

From the foregoing description it will be apparent that the heavy-media separation of the present invention affords many advantages. The low head design simplifies mill arrangements, and due to the pulp ratios employed, a relatively large tonnage of ore can be treated in standard sized classifiers to which the features of the present invention have been applied.

Apparatus in use at present utilizes an air lift to elevate the sink concentrate and heavy medium to a drainage and washing screen and as noted heretofore, the percentage weight of dry concentrate in the air lift discharge is relatively small compared to the total weight of medium and sink concentrate that must be elevated.

The operation of the present invention results in delivery of a mixture of sink concentrate and medium in which the percentage weight of sink concentrate is relatively high. The economies effected due to this fact are:

1. Elimination of an air compressor;
2. Elimination of the drainage section of the former drainage and washing screen;
3. A reduction in the size of the pump required to return heavy medium to the separating apparatus, from which it follows that less power is required for this work;

4. The rotation of shaft 36 and spiral conveyor 35 in the machine of Figure 2 performs a double duty of conveying sink concentrate and agitating the mass of medium to maintain a constant density of heavy medium, whereas in apparatus in present use separate devices, both of which require power, are required to perform these essential duties.

For this reason, a relatively simple treatment circuit of the type shown in Figure 1 is all that is required in attaining efficient separation. Consequently, both initial costs and operating expenses are quite nominal as compared with other types of heavy-media separations.

The invention has been described with particular reference to iron ore treatments for which it is well suited, but it also may be utilized in the treatment of other materials. Fluorspar and lead-zinc ores are examples, although the treatment may be practiced with almost any material where the separation of gangue and mineral can be made at relatively coarse sizes.

It will be noted that in both the forms shown in Figures 2 and 6, the separation and conveying and drainage zones are physically separated but have a communicating passage between their lower portions. Due to the high density pulp body in the conveying and drainage zone, sufficient pressure is exerted on the heavy-media body to keep it confined in the separation zone.

Of course, some heavy-media passes into the conveying and drainage zone with the sink prod-

uct, but the agitative action of the pool combined with the tumbling imparted to the raked product in its progressive movement away from the pool, serves to release a substantial amount of the entrained heavy-media which drains back into the pool.

To facilitate this action in the conveying and drainage compartment, it is preferred to use a spiral conveyor of multiple ribbon construction and thereby provide separate blades 35a and 35b operating in close proximity to passage 44. Consequently, solids entering the conveying and drainage compartment are acted on by the blades without undue delay and are progressively moved through the pool and upwardly along the inclined bottom to the elevated discharge outlet.

While the invention has been illustrated and described with reference to simplex type classifiers, it will be apparent that the same relationship can be provided between the separation compartment and the conveying and drainage zone of a duplex type classifier. The accompanying drawings are intended to illustrate typical embodiments of the invention and corresponding arrangements can be incorporated in a variety of apparatus.

Under certain conditions it may be preferable to vary the size of the feed opening and an adjustable baffle or gate may be provided for this purpose. Similarly, it may be desirable to vary the vertical dimension of the separation zone and this can be accomplished by placing slats as an adjustable weir on the overflow lips 42 and 51.

Despite all these variations in the structural features, the separations performed are essentially the same, and changes and modifications may be availed of within the spirit and scope of the invention as defined in the hereunto appended claims.

What I claim and desire to secure by Letters Patent is:

1. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone disposed in end-to-end relation, and said partition being spaced from the tank bottom to provide a passage between said zones, a body of heavy-media in the separation zone, a feed box in the separation zone having its intake above the weir overflow level and having its lower end submerged in the heavy media, a body of pulp in the conveying and drainage zone exerting pressure on the heavy-media through said passage, and conveying means in the conveying and drainage zone for moving settled solids through the pulp body and upwardly along the sloping bottom to a point of discharge at a higher elevation than said pulp body.

- 65 2. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone disposed in end-to-end relation and said partition being spaced from the tank bottom to provide a passage between said zones, a body of

heavy-media in the separation zone, a reed box in the separation zone having its intake above the weir overflow level and having its lower end submerged in the heavy-media, a body of high density pulp in the conveying and drainage zone exerting pressure on the heavy-media through said passage, and conveying means in the conveying and drainage zone for moving settled solids through the pulp body and upwardly along the sloping bottom to a point of discharge at a higher elevation than said pulp body.

3. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone disposed in end-to-end relation and said partition being spaced from the tank bottom to provide a passage between said zones, a body of heavy-media in the separation zone, an open-ended feed-box in the separation zone having its intake above the weir overflow level and having its lower end submerged in the heavy-media, a body of pulp in the conveying and drainage zone exerting pressure on the heavy-media through said passage, and conveying means in the conveying and drainage zone for moving settled solids through the pulp body and upwardly along the sloping bottom to a point of discharge at a higher elevation than said pulp body.

4. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone disposed in end-to-end relation and said partition being spaced from the tank bottom to provide a passage between said zones, a body of heavy-media in the separation zone, a feed-box in the separation zone having its intake above the weir overflow level and having its lower end submerged in the heavy media, means for varying the volumetric capacity of said separation zone, a body of pulp in the conveying and drainage zone exerting pressure on the heavy-media through said passage, and conveying means in the conveying and drainage zone for moving settled solids through the pulp body and upwardly along the sloping bottom to a point of discharge at a higher elevation than said pulp body.

5. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone disposed in end-to-end relation and said partition being spaced from the tank bottom to provide a passage between said zones, a body of heavy-media in the separation zone, a feed-box in the separation zone having its intake above the weir overflow level and having its lower end submerged in the heavy-media, a body of high density pulp in the conveying and drainage zone exerting pressure on the heavy-media through said passage, and a spiral conveyor in the conveying and drainage zone for moving settled solids

through the pulp body and upwardly along the sloping bottom to a point of discharge at a higher elevation than said pulp body.

6. Apparatus for heavy-media separations, comprising a tank having three sides and a sloping bottom, one of said sides including an overflow weir, a partition adjacent the lower end of the tank dividing its interior into a separation zone and a conveying and drainage zone and spaced from the tank bottom to provide a passage between said zones, a body of heavy-media in the separation zone, a feed-box in the separation zone having its intake above the weir overflow level and having its lower end submerged in the heavy-media, a splitter disposed beneath the feed-box to distribute solids descending therethrough, a body of pulp in the conveying and drainage zone exerting pressure on the heavy-media through said passage, and conveying means in the conveying and drainage zone for moving settled solids through the pulp body and upwardly along the sloping bottom.

7. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone and spaced from the tank bottom to provide a passage between said zones, a body of heavy-media in the separation zone, a feed-box in the separation zone having its intake above the weir overflow level and having its lower end submerged in the heavy media, adjustable partition means constructed and arranged to vary the volumetric capacity of the separation zone for exerting a crowding action on the float product in the separation zone, a body of pulp in the conveying and drainage zone exerting pressure on the heavy-media through said passage, and conveying means in the conveying and drainage zone for moving settled solids through the pulp body and upwardly along the sloping bottom to a point of discharge at a higher elevation than said pulp body.

8. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone disposed in end-to-end relation and said partition being spaced from the tank bottom to provide a passage between said zones, a body of heavy-media in the separation zone, a body of pulp in the conveying and drainage zone exerting pressure on the heavy-media through said passage, means for feeding heavy-media and ore to the separation zone, and conveying means in the conveying and drainage zone for moving settled solids through the pulp body and upwardly along the sloping bottom to a point of discharge at a higher elevation than said pulp body.

9. Apparatus for heavy-media separations, comprising a tank having three sides and a sloping bottom, one of said sides including an overflow weir, the level of which is lower than the upper end of said sloping bottom, a partition adjacent the lower end of the tank dividing its interior into a relatively small separation zone and a relatively large conveying and drainage zone

75 a relatively large conveying and drainage zone

disposed in end-to-end relation and said partition being spaced from the tank bottom to provide a passage between said zones, a body of heavy-media in the separation zone, a body of pulp in the conveying and drainage zone exerting pressure on the heavy-media through said passage, means for feeding heavy-media and ore to the separation zone, and conveying means in the conveying and drainage zone positioned to act on solids traveling through the passage to move said solids progressively through the pulp body and upwardly along the sloping bottom to a point of discharge at a higher elevation than said pulp body.

10. Apparatus for heavy-media separations, comprising a tank having three sides and a sloping bottom, one of said sides including an overflow weir, the level of which is lower than the upper end of said sloping bottom, a partition adjustably mounted adjacent the lower end of the tank to divide its interior into a relatively small separation zone and a relatively large conveying and drainage zone disposed in end-to-end relation and movable to differently spaced positions relative to the tank bottom to provide a passage between said zones, a body of heavy-media in the separation zone, a feed-box in the separation zone having a submerged outlet in the heavy-media body, a body of pulp in the conveying and drainage zone exerting pressure on the heavy-media through said passage, and conveying means in the conveying and drainage zone for moving settled solids through the pulp body and upwardly along the sloping bottom to a point of discharge at a higher elevation than said pulp body.

11. The heavy media separation process which comprises maintaining a pool of relatively large volume and a pool of relatively small volume in end to end relation with a restricted flow path from the bottom of the small volume pool into the lower portion of the other pool, maintaining a common level for said pools by the continuous overflow of float material from the surface of the small volume pool, maintaining a body of heavy media in the small volume pool between the restricted flow path and the surface of the pool, continuously introducing material to be separated into said heavy media body, moving the sink product descending through the restricted zone into said larger volume pool upwardly along an inclined course through and out of said pool to a point of discharge above the pool, and agitating the solids in the larger volume pool to maintain in suspension a substantial portion of the sink product content to thereby create a high density head directed against the restricted zone to restrict settling of float material into said zone.

12. The heavy media separation process which comprises maintaining a pool of relatively large volume and a pool of relatively small volume in end to end relation with a restricted flow path from the bottom of the small volume pool into the lower portion of the other pool, maintaining a common level for said pools by the continuous overflow of float material from the surface of the small volume pool, maintaining a body of heavy media in the small volume pool between the restricted flow path and the surface of the pool, continuously introducing material to be separated into said heavy media body, moving the sink product descending through the restricted zone into said larger volume pool upwardly along an inclined course through and out of said pool

to a point of discharge above the pool, agitating the solids in the larger volume pool to maintain in suspension a substantial portion of the sink product content to thereby create a high density head directed against the restricted zone to restrict settling of float material into said zone, separating entrained media from the sink product moving out of the larger volume pool along the inclined course, and returning the separated media to the high density body in said larger volume pool.

13. The heavy media separation process which comprises maintaining a pool of relatively large volume and a pool of relatively small volume in end to end relation with a restricted flow path from the bottom of the small volume pool into the lower portion of the other pool, maintaining a common level for said pools by the continuous overflow of float material from the surface of the small volume pool, maintaining a body of heavy media in the small volume pool between the restricted flow path and the surface of the pool, continuously introducing material to be separated into said heavy media body, moving the sink product descending through the restricted zone into said larger volume pool upwardly along an inclined course through and out of said pool to a point of discharge above the pool, agitating the solids in the larger volume pool to maintain in suspension a substantial portion of the sink product content to thereby create a high density head directed against the restricted zone to restrict settling of float material into said zone, and varying the effective volume of the smaller volume pool against which the high density head is directed.

14. The heavy media separation process which comprises maintaining a pool of relatively large volume and a pool of relatively small volume in end to end relation with a restricted flow path from the bottom of the small volume pool into the lower portion of the other pool, maintaining a common level for said pools by the continuous overflow of float material from the surface of the small volume pool, maintaining a body of heavy media in the small volume pool between the restricted flow path and the surface of the pool, continuously introducing material to be separated into said heavy media body, moving the sink product descending through the restricted zone into said larger volume pool upwardly along an inclined course through and out of said pool to a point of discharge above the pool, agitating the solids in the larger volume pool to maintain in suspension a substantial portion of the sink product content to thereby create a high density head directed against the restricted zone to restrict settling of float material into said zone, collecting entrained media passing with the sink product into the larger volume pool from the smaller volume pool, and inducing a return of a portion of said media to the smaller volume pool under the impelling influence of the high density head.

15. The heavy media separation process which comprises maintaining a pool of relatively large volume and a pool of relatively small volume in end to end relation with a restricted flow path from the bottom of the small volume pool into the lower portion of the other pool, maintaining a common level for said pools by the continuous overflow of float material from the surface of the small volume pool, maintaining a body of ferro-silicon in the small volume pool between the restricted flow path and the surface of the

11

pool, continuously introducing material to be separated into said ferro-silicon body, moving the sink product descending through the restricted zone into said larger volume pool upwardly along an inclined course through and out of said pool to a point of discharge above the pool, and agitating the solids in the larger volume pool to maintain in suspension a substantial portion of the sink product content to thereby create a high density head directed against the restricted zone to restrict settling of float material into said zone.
